(57) **CLAIM**

The ornamental design for seal member for use in semiconductor production apparatus, as shown and described.

DESCRIPTION

1.1 is a perspective view of a seal member for use in semiconductor production apparatuses, showing our new design;

1.2 is a front elevation view thereof;

1.3 is a rear elevation view thereof;

1.4 is a left side elevation view thereof;

1.5 is a right side elevation view thereof;

1.6 is a top view thereof;

1.7 is a bottom view thereof;

1.8 is an enlarged left side elevation view thereof; and

1.9 is an enlarged left side elevation view thereof in a condition of use.

The broken lines shown in Reproduction 1.9 are for the purposes of illustrating environmental structure and form no part of the claimed design.
